UNITED STATES PATENT OFFICE.

RICHARD EVANS ELETT, OF LONDON, ENGLAND.

DESIGN FOR A TOY ANIMAL.

Application filed September 27, 1926. Serial No. 19,182. Term of patent 7 years.

To all whom it may concern:

Be it known that I, RICHARD EVANS ELETT, a subject of the King of Great Britain, residing at London, England, have invented a new, original, and ornamental Design for a Toy Animal, of which the following is a specification, reference being made to the accompanying drawing, forming part thereof.

The figure is a front perspective view of a toy animal showing my new design.

I claim:

The ornamental design for a toy animal as shown.

RICHARD EVANS ELETT.
